UNITED STATES PATENT OFFICE

ELMER H. STUART, OF INDIANAPOLIS, INDIANA, ASSIGNOR TO ELI LILLY AND COMPANY, OF INDIANAPOLIS, INDIANA, A CORPORATION OF INDIANA

EPHEDRINE-ALDEHYDE COMPOUND AND SOLUTION AND PROCESS OF PREPARING SUCH COMPOUND

No Drawing.

Application filed May 3, 1928. Serial No. 274,965.

My present invention relates to certain new chemical compounds, involving the combination of an ephedrine with aldehydes, to oil solutions of such compounds, and to the process of preparing such compounds.

These new compounds have certain advantages in connection with the use of ephedrine, especially in certain physiological treatments; as they appear to be quite generally less irritating than the alkaloid ephedrine itself, in many instances are oil-soluble or at least more oil-soluble than the alkaloid ephedrine itself, in most instances are substantially equally physiologically active.

In using the term "an ephedrine," I have in mind not only the levo-rotatory ephedrine which is now most commonly known by that name, but also the various isomeric forms of ephedrine of the general formula:

20

I have made a number of these compounds of an ephedrine with aldehydes. For instance, I have combined an ephedrine with formaldehyde, acetaldehyde, phenylacetaldehyde, heptaldehyde, anisaldehyde, furfuraldehyde, salicylaldehyde, vetratraldehyde, citral, vanillin, benzaldehyde, o-methoxybenzaldehyde, and cinnamic aldehyde; sometimes using ordinary l-ephedrine and sometimes d-pseudoephedrine. The combinations of the aldehydes with ordinary l-ephedrine, which is levo-rotatory, are the ones that are physiologically the most active.

So far as I am aware, all these ephedrine-aldehyde compounds are new with me with the exception of ephedrine-benzaldehyde and pseudoephedrine-benzaldehyde; and my process of forming such compounds, and my oil solutions of such compounds, are new with me as to all such compounds without exception.

The compounds of ephedrine and pseudoephedrine with benzaldehyde have been described, in a paper by Ernest Schmidt beginning on page 89 of Archiv der Pharmazie for 1914. In that paper it is pointed out

that benzaldehyde is an oxidation-decomposition product of ephedrine and of pseudoephedrine, and that such benzaldehyde combines with ephedrine and with pseudoephedrine to form benzal-ephedrine and benzal-pseudoephedrine respectively.

However, that article describes no compounds of either ephedrine or pseudoephedrine with any aldehyde save benzaldehyde; which, as the paper points out, is an oxidation-decomposition product of ephedrine and pseudoephedrine. Thus it is new with me, so far as I know, to provide compounds of an ephedrine with an aldehyde which is not itself an oxidation-decomposition product of an ephedrine.

Neither does that article describe the process which is set forth in the present application of producing an ephedrine-aldehyde, even in the case where the aldehyde is benzaldehyde. Thus such process is new with me, so far as I know, for any ephedrine-aldehyde compound, including the compounds where the aldehyde component is benzaldehyde.

In making these compounds, the combination is apparently in the proportion of one molecule of an ephedrine to one molecule of the aldehyde, with the elimination of one molecule of water. I am not prepared to give definitely the chemical structures of the resulting compounds; but in all instances it appears that definite compounds are formed, with definite physical properties, and in some instances with the development of considerable heat in the reaction.

In producing these compounds, I find it convenient to dissolve the desired amount of an ephedrine in ether, and then to add the aldehyde, in substantially the theoretical amount for a 1-to-1 molecular combination, to the ether solution of the ephedrine. If the aldehyde is itself liquid, as in the case of acetaldehyde, it may be poured directly into the ether solution of the ephedrine; whereas if the aldehyde is a solid at ordinary temperatures, as in the case of vanillin, I may dissolve it separately in ether and then mix the ether solution of the aldehyde and the ether solution of the ephedrine.

The combination usually takes place at

75

80

85

90

95

100

ordinary temperatures, but sometimes slight heating is used to start the reaction. In some instances, notably in the case of the combination of the ephedrine with acetaldehyde, considerable heat of reaction is developed.

If ether is used, it may be removed; as by distillation to drive off most of the ether, and then by vacuum evaporation over a water bath to remove the remaining ether.

10 During the last part of the evaporation of the ether, the water which is formed by the reaction is usually noticed as separate from the ephedrine-aldehyde compound produced; and this water may be removed by the last 15 part of the vacuum evaporation.

The final results thus obtained have definite physical properties.

10 The compound of d-pseudo-ephedrine and formaldehyde is a liquid at ordinary temperatures, with a slight yellow color.

15 The compound of ordinary l-ephedrine with acetaldehyde is a liquid at ordinary temperatures, having a slight yellow color, with a boiling point of 239° C. Its refractive index at 25° C. is 1.5112. This compound of acetaldehyde with ordinary l-ephedrine appears to be rather unstable, as in the course of several weeks it develops a somewhat different odor, its original odor being something 30 like that of acetaldehyde, and the odor later being something like that of phosphorus. An assay of the fresh compound of ordinary l-ephedrine and acetaldehyde shows it to contain the equivalent of 85% of its weight of 35 the original alkaloid; which is fairly close to the theoretical value of 86.4% in a combination in the proportion of one molecule of ephedrine to one molecule of acetaldehyde with the elimination of one molecule of water.

40 The compound of ordinary l-ephedrine with furfuraldehyde is a solid at ordinary temperatures. Its melting point is 48° C. It appears to be unstable, as its odor changes on standing.

45 The compound of ordinary l-ephedrine with citral is a liquid at ordinary temperatures. It has a viscosity comparable with that of light paraffin oil.

50 The compound of ordinary l-ephedrine with heptaldehyde is a colorless liquid at ordinary temperatures. In absolute alcohol at 25° C., it has an optical rotation of -42.8°.

55 The compound of ordinary l-ephedrine with benzaldehyde is a white crystalline solid at ordinary temperatures. Its melting point is 73° C. It can be purified by recrystallization from 95% alcohol. In absolute alcohol at 25° C., it has an optical rotation of -53.1°. This compound is described in the aforesaid 60 Schmidt paper, but my method of preparing it is not there described.

65 The compound of ordinary l-ephedrine with anisaldehyde is a white crystalline powder. It can be purified by recrystallization from 95% alcohol. Its melting point is

89.5° C. Its optical rotation when dissolved in absolute alcohol at 25° C. is -54.4°.

The compound of ordinary l-ephedrine with o-methoxy-benzaldehyde is a white crystalline powder. Its melting point is 70 103.5° C. It can be purified by recrystallization from absolute alcohol.

The compound of ordinary l-ephedrine with salicylaldehyde is a white crystalline powder. Its melting point is 75 117° C. It can be purified by recrystallization from absolute alcohol.

The compound of l-ephedrine with vitraldehyde is a white crystalline powder when recrystallized from absolute alcohol. 80 Its melting point is 97° C.

The compound of ordinary l-ephedrine with vanillin is a resin-like solid at ordinary temperatures, having initially a slight yellow 85 color that changes to a yellowish red upon standing. Its melting point is not definite. This compound of ordinary l-ephedrine with vanillin appears not to be entirely stable, as evidenced by the change in color above noted.

The compound of ordinary l-ephedrine with cinnamic aldehyde is a solid at ordinary 90 temperatures. It is a white crystalline powder which can readily be purified by recrystallization from 95% alcohol. It has a melting point of 92.5° C. When dissolved in absolute alcohol at 25° C., it has an optical rotation of -74.3°. This compound of ordinary l-ephedrine with cinnamic aldehyde appears to be quite stable. An assay of the compound of ordinary l-ephedrine and cinnamic aldehyde shows it to contain the equivalent of 58.9% of its weight of the original 100 alkaloid; whereas theoretically the combination in the proportion of one molecule of ephedrine to one molecule of cinnamic aldehyde, less one molecule of water, is 59.14% of alkaloid.

I have hydrolyzed the compound of cinnamic aldehyde and l-ephedrine by means of acid alcohol, and re-obtained the original 110 ordinary l-ephedrine unchanged.

The compound of d-pseudo-ephedrine with cinnamic aldehyde is a white crystalline powder, which can be purified by re-crystallization from absolute alcohol. It has a melting point of 75° C. When dissolved in absolute alcohol at 25° C., it has an optical rotation of + 32.9°.

The compound of d-pseudo-ephedrine and benzaldehyde is a solid at ordinary temperatures, with a melting point of 67° C. An assay shows an equivalent of 64.48% d-pseudo-ephedrine. This compound is described in the aforesaid Schmidt paper, but my method of preparing it is not there described.

The compound of salicylaldehyde with d-pseudo-ephedrine is a solid at ordinary temperatures, with a melting point of about 79 to 80° C.

The compound of d-pseudo-ephedrine and

vanillin is a solid at ordinary temperatures, with a melting point of about 124.5 to 125° C.

The foregoing are merely a few examples of a number of compounds of this nature which may be produced.

5 The physical properties given above for the various compounds may be found to vary slightly upon further purification. For instance, the compounds which are described 10 as having a slight yellow color may be found on further purification to be white.

Most of these compounds are oil-soluble to a greater or less extent. The compounds of ordinary L-ephedrine with acetaldehyde, 15 citral, heptaldehyde, and cinnamic aldehyde are soluble in paraffin oil as a menstruum to at least 2% or more, at a temperature of 15° C. or higher, and when so dissolved the resultant oil solutions are found to be suitable 20 as oil-ephedrine inhalants or nasal sprays; while the other compounds mentioned are in general less soluble than those four. Those which are less soluble can nevertheless be dissolved in paraffin oil if certain other substances are added; as for instance ethyl alcohol or isopropyl alcohol, or some additional 25 ephedrine over that necessary for the 1-1 molecular proportion.

The fairly ready oil solubility of these 30 compounds of an ephedrine with aldehydes makes them readily available for use in oil, as for application in the nose. Most of these oil solutions when used as nasal sprays or inhalants are substantially non-irritating to 35 the mucous membranes, and all of them are apparently less irritating than is the oil solution of the alkaloid ephedrine itself.

In addition to the aldehyde-ephedrine compounds which are oil-soluble to a greater 40 or less extent, there are some such compounds which are oil-insoluble.

The compound of ordinary L-ephedrine with protocatechuic aldehyde is a red-brown 45 resin-like solid at ordinary temperatures; and is practically insoluble in paraffin oil.

The compound of ordinary L-ephedrine with p-hydroxy-benzaldehyde is a blood-red 50 resin-like solid at ordinary temperatures; and is practically insoluble in paraffin oil.

55 All of these compounds, both those which are oil soluble and those which are oil-insoluble, are soluble in alcohol.

I claim as my invention:

1. A compound obtained by the reaction of 55 1 mol of L-ephedrine with 1 mol of an aldehyde other than one which is an oxidation-decomposition product of such ephedrine.

2. A compound obtained by the reaction of 60 1 mol of an ephedrine with 1 mol of an aldehyde other than one which is an oxidation-decomposition product of such ephedrine, with the elimination of 1 mol of water.

3. A compound which is produced by the 65 re-action of an ephedrine with an aldehyde other than one which is an oxidation-decom-

position product of such ephedrine, with the elimination of water.

4. The process of producing a compound between an ephedrine and an aldehyde, which consists in bringing them together in a solvent in which both the ephedrine and aldehyde are freely soluble.

5. The process of forming a compound of 70 an ephedrine with an aldehyde, which consists in dissolving the ephedrine in ether, and adding to the resultant solution an ether solution of an aldehyde.

6. The process of forming a compound of 75 an ephedrine with an aldehyde, which consists in dissolving the ephedrine in ether, and adding to the resultant solution an aldehyde.

7. The process of forming a compound of 80 an ephedrine with an aldehyde, which consists in dissolving the ephedrine in a solvent which is capable of dissolving both the ephedrine and aldehyde, and adding to the resultant solution a solution of the aldehyde in the same solvent.

8. A compound which is produced by the 85 re-action of L-ephedrine with an aldehyde other than one which is an oxidation-decomposition product of such ephedrine.

9. A nasal spray, consisting in oil as a 90 menstruum, and a compound dissolved therein that is obtained by the reaction of one mol of L-ephedrine with one mol of an aldehyde.

10. A nasal spray, consisting in oil as a 95 menstruum, and a compound dissolved therein that is obtained by the reaction of one mol of an ephedrine with one mol of an aldehyde.

11. A nasal spray, consisting in oil as a 100 menstruum, and a compound dissolved therein that is produced by the reaction of ephedrine with an aldehyde.

12. A nasal spray, consisting in oil as a 105 menstruum, and a compound dissolved therein that is produced by the reaction of L-ephedrine with an aldehyde.

In witness whereof, I have hereunto set my 110 hand at Indianapolis, Indiana, this 1st day of May, A. D. one thousand nine hundred and twenty-eight.

ELMER H. STUART.
